SHEET DECURLING APPARATUS

Lynn O. Hayes, St. Louis, Mo., assignor to F. L. Smithe Machine Co., Inc., New York, N. Y., a corporation of New York

Application October 24, 1941, Serial No. 416,294

9 Claims. (Cl. 93—61)

This invention relates to improvements in sheet decurling apparatus, and especially to such apparatus adapted for removing the curl from the trailing portion of a traveling sheet or blank. It is especially adapted to decurling the closure flaps of envelope blanks while the blanks travel through an envelope folding machine, eliminating the curl in such flap caused by the dried gum extending along the flap margin.

A general purpose of the invention is to provide an improved decurling construction which may be shifted into and out of decurling engagement with a traveling sheet or blank in appropriate timed relation to the travel of the blank. A further purpose is the provision of such apparatus which is adapted to be mounted on and actuated by standard machines, in which the sheets or blanks are continuously conveyed in series to successive operating devices, such as flap gumming and folding mechanisms.

Another purpose is the provision of a novel arrangement for adjusting the relationship of the decurling members to adapt the apparatus to different conditions and types of sheet material; and in the preferred form the invention includes a construction for adjusting the decurling members both longitudinally of and transversely to the path of the sheets or blanks.

The present invention is in the nature of an improvement upon the invention disclosed and claimed in my copending application Serial No. 416,293, filed October 24, 1941. No claim is made herein to the feature of adjusting the guide member and the decurling member relative to one another longitudinally of the sheet path for the reason that that subject-matter is claimed in the copending application referred to.

Other objects and advantages will appear from the following description considered in connection with the accompanying drawings in which:

Fig. 1 is a vertical sectional view through a decurling apparatus incorporated in an envelope folding machine, with parts omitted, showing the decurling apparatus in non-operating position;

Fig. 2 is a similar view with the apparatus in operative or decurling position;

Fig. 3 is a plan view of an envelope blank with the closure flap trailing in position for decurling;

Fig. 4 is a vertical sectional view on line 4—4 of Fig. 1;

Fig. 5 is a plan view of the construction shown in Figs. 1, 2 and 4 with parts broken away;

Fig. 6 is a fragmentary horizontal sectional view showing the mounting and arrangement of the decurling members;

Fig. 7 is a view similar to Fig. 1 showing a modified construction in inoperative position;

Fig. 8 is a similar view of the modified construction in operative position; and

Fig. 9 is a side elevation of the modified construction viewed from line 9—9 of Fig. 7.

In the illustrated embodiment of the invention the decurling apparatus is mounted on an envelope folding machine and is actuated by the drive mechanism of such machine, which advantageously is of the type shown in the patent to Abraham Novick, No. 1,607,867 issued June 2, 1931. In machines of this type the envelope blank is subjected to a series of operations including folding the side flaps, gumming the bottom flap, folding the bottom flap into adhesive engagement with the side flaps, and finally folding the closure flap into place. While the decurling apparatus may be located at different stages in the folding operations, it is advantageously arranged to decurl the closure flap after the bottom flap has been folded into place and immediately preceding the final folding of the closure flap. Moreover, the decurling apparatus is especially designed and adapted for location between blank advancing devices such as pairs of rolls, and is constructed and arranged to permit free passage of the advance margin of the blank from the first pair of rolls to the second pair, thereafter coming into decurling engagement with the trailing flap portion of the blank after the latter has been engaged by the second pair of rolls, and advantageously after the flap has been released by the first pair.

In the illustrated arrangement the envelope folding machine includes a pair of side frames 10 carrying two pairs of feed rolls 11, 12 and 13, 14 suitably driven in known manner to advance the envelope blank 15, with closure flap 16 trailing, along aligned table sections 17, 18 and 19.

Table section 18 is mounted on suitable ears 20, Fig. 4, on frame 10 by screws 21. The decurling apparatus includes two members extending transversely at opposite sides of the envelope path and spaced therefrom when in inoperative position, one member being movable into overlapping relationship to the other member while the envelope blank is passing between the members, the arrangement being such that the curled portion of the flap is bent across the second member and is decurled by being drawn across said member by rolls 13 and 14.

The decurling members and their actuating mechanism are arranged for support by the

frames 10; and in the preferred embodiment illustrated are mounted on table section 18. In this particular construction the upper member 22 is stationary and consists of a flat bar 23 extending across and above the path of the blank 15 which travels along the registering upper surfaces of table sections 18 and 19, bar 23 being provided at each end with a downward extension or leg 24 having a mounting flange 25 resting on and attached to table section 18.

A suitable construction is advantageously provided for adjusting the upper decurling member 22 longitudinally of the envelope path. This is conveniently accomplished in the illustrated arrangement by providing each mounting flange 25 with a transverse slot 26, Fig. 6, fitting an eccentric shank 27 of adjusting post 28, the head 29 of which extends over and engages mounting flange 25 at either side of slot 26 and is held in position by mounting screw 30 threaded into table section 18, Fig. 4. Screw 30 is eccentric to shank 27, but is advantageously concentric with head 29 and countersunk therein, the arrangement being such that by releasing screws 30 the adjusting posts 28 may be rotated to shift the ends of upper decurling member 22, slots 26 being of sufficient length to permit proper positioning of the member with relation to the sides of the envelope path. Member 22 may then be clamped in adjusted position by tightening screws 30.

The lower decurling member 35 comprises a flat bar 36 located a short distance to the rear of upper bar 23 with relation to the direction of travel of the blanks 15, bar 36 being located below the level of the upper faces of table sections 18 and 19 when in inoperative position, and being movable upwardly between said sections into overlapping juxtaposition to the lower margin of bar 23 for decurling the flap 16. Suitable mechanism carried by frames 10 is provided for supporting and shifting the lower decurling member 35 between operative and inoperative positions. In the illustrated embodiment decurling member 35 is mounted on table section 18. For this purpose bar 36 is provided at each end with an upward extension 37 carrying a pin 38 journaled in the lower end of hanger links 39 which are journaled on lift rod 40. Rock arms 41 are fixed to rod 40 in contact with links 39, and the end of each arm 41 is journaled on a headed pivot pin 42 mounted on a standard 43 attached to table section 18 by screw 44. Each hanger link 39 is appropriately held in place on rod 40 as by collar 45 fixed to said rod.

An appropriate construction for raising and lowering lift rod 40 to move decurling member 35 to and from operative position is provided, and in the form shown in Figs. 1, 4 and 5 includes a lift arm 46 fixed to an end of rod 40 extending through opening 48 in a frame 10. Arm 46 is provided with a longitudinal slot 47 in which pivot pin 48 is adjustably clamped, the pivot pin including a headed collar 49 slidable in slot 47 and threaded on the shank of pivot screw 50 having an enlarged pivot section 51, arranged so that by tightening screw 50 with the pivot 48 in appropriate position in slot 47 the collar 49 and washer 52, bearing against lift arm 46 and pivot section 51, are clamped tightly against opposite sides of said arm. Drive link 53, journaled on pivot section 51 and normally biased downwardly by spring 54 attached to adjacent frame 10, is lifted in appropriate timed relation to the feed of envelope blanks 15 by a suitable cam (not shown)

mounted on and actuated by the drive of the folding machine.

A suitable construction is advantageously provided for adjusting the position of the upper decurling member 22 relative to the lower decurling member 35 transversely to the envelope path, thereby varying the amount of overlap between the members and the resulting decurling action. This is accomplished by varying the throw of drive link 53 through adjustment of pivot pin 48 in slot 47; but it may be done also by an adjustment that does not change materially the throw or stroke of the oscillating frame which supports member 35. In the illustrated construction this is accomplished by constructing pivot pin 42 with an end portion 55 rotatable in standard 43, and a body 56 eccentric to the end 55 and rotatable in a bore in rock arm 41, set screw 57 in standard 43 engaging the pivot end 55 to hold the body 56 in adjusted position.

A suitable guide construction is provided for controlling the path of the lower decurling member 35, and advantageously comprises vertical guides slidably engaged by end portions of bar 36 or extensions thereof. In the form illustrated in Figs. 1, 4 and 5 each bar extension 37 slidably fits a vertical guideway 58 in the contiguous standard 43.

A modified construction for supporting and actuating the decurling members 22 and 35 is shown in Figures 7, 8 and 9. In this arrangement each pin 38 on the lower decurling member 35 is journaled in the lower end of an elongated hanger link 60, which is held on the pin 60a by collar 61 and set screw 62. The upper end of each link 60 is pivoted on headed pivot pin 63 carried by rock arm 64 fixed to rock shaft 65 as by split clamp 66. Shaft 65 is journaled in ears 67 on standards 68 fixed to frames 10 by screws 69, and is held in place by collars 71. Shaft 65 is rocked by arm 70 fixed to its outer end, arm 70 being constructed, arranged and actuated in the same way as arm 45 above described.

In this embodiment a suitable construction is provided for adjusting the position of the lower decurling member 35 longitudinally to the path of the blanks, thereby varying the spacing between said member and the upper decurling member 22 when the members are in operative position. This is in general accomplished by providing a guide construction controlling the path of movement of the member 35, and adjusting the position of such guide construction.

In the form illustrated in Figs. 7, 8 and 9 this construction includes a slot or guideway 74 at each side of the path of the blanks formed between guide flanges 75 on guide arm 76 and slidably fitting each upward extension 37 of decurling member 35. Each guide arm 76 is mounted for the requisite longitudinal adjustment, as by pivoting the arm above the uppermost position of decurling member 35 by means of pivot pin 77 threaded into arm 76 and countersunk in a suitable bore in standard 68. Arm 76 is clamped in adjusted position as by clamp screw 78 threaded into standard 68 through adjustment slot 79, Fig. 8, in arm 76. By releasing screw 78 the upper end of arm 76 may be shifted, moving guide flanges 75 about pivot 77 and shifting the lower decurling member 35 longitudinally of the blank path, the distance between said member and pivot pin 77 being such that the change in the angle of said member is insufficient to affect the decurling operation.

In this construction table sections 18 and 19

are spaced sufficiently to permit the requisite longitudinal adjustment of member 35; and the upper decurling member 22 may be held in fixed position on table section 18, though this showing is illustrative rather than restrictive, since obviously the adjustable mounting for member 22 disclosed in the embodiment first described may be employed in that shown in Figs. 7, 8 and 9 if it is considered desirable.

In operation, the envelope blanks 15 pass in series through the folding machine, which is provided with suitable mechanism for conveying each blank continuously through the side flap folding mechanism, the bottom flap gumming mechanism and the bottom flap folding mechanism, and thence along table section 17 to rollers 11, 12, which engage the leading edge of a blank and advance it over table sections 18 and 19 to the bight of rollers 13 and 14. During this operation the lower decurling member 35 is in lowermost position with its upper margin below the level of the table sections 18 and 19, so that the blank 15 may pass over member 35 without interference. The upper member 22 is clear of the normal path of the blank; but if the blank should be accidentally deflected upwardly into contact with member 32, the downwardly inclined guide face 31 will guide the blank edge under member 22 and avoid interference with the advance of the blank to rollers 13, 14.

The rollers are arranged so that rollers 13, 14 will engage the blank 15 before it is completely released by rollers 11, 12; and the decurling members 22, 35 are positioned and actuated so that they will come into decurling engagement with the forward portion of the trailing closure flap 16 after the blank 15 has been engaged by rollers 13, 14 and released by rollers 11, 12. When lower decurling member 35 is raised into operative position by cam action on drive link 53 the flap 16 will be bent over the decurling edge 32 of member 35 by guide edge 33 of decurling member 22, as shown in Fig. 2; and the curl in flap 15 will be straightened by drawing the flap across edge 32 in the indicated bent position through the action of rollers 13, 14.

The decurling action, as well as the adaptability of the device to different types of sheet material, is regulated either by varying the spacing of members 22 and 35 in the direction of sheet travel, by varying the extent to which member 35 overlaps member 22 when in operative position, or by a combination of these two adjustments. In the arrangement shown in Fig. 1 the adjacent margin of table sections 18 and 19 may be appropriately spaced to serve as guides for the lower decurling member 35. In the arrangement shown in Figs. 7-9 the corresponding margins of table sections 18 and 19 are sufficiently spaced to permit adjustment of lower decurling member 35 lengthwise of the sheet path without interference with said table sections. The engagement of member 35 with the proper portion of the envelope blank is assured by actuating the decurling device from the folding machine drive in obvious manner.

The disclosed construction is compact, convenient and capable of ready assembly and disassembly in whole or in part. It is arranged to provide a compact unit which can be separately assembled and rapidly and readily applied to or removed from an envelope folding machine. It is in particular arranged to fit between pairs of sheet feeding rollers of standard type and arrangement. Moreover, the decurling members

are provided with separate adjustments at each side of the sheet path so that accurate alignment, parallelism and spacing may be readily obtained.

5 I have described what I believe to be the best embodiments of my invention. I do not wish, however, to be confined to the embodiments shown, but what I desire to cover by Letters Patent is set forth in the appended claims.

10 I claim:

1. Sheet decurling apparatus comprising registering decurling members located on opposite sides of the path of a traveling sheet, actuating mechanism for shifting one of the members into decurling position adjacent to and overlapping the other member, and adjusting mechanism for varying the location of the latter member in decurling position in a direction transverse to the path of the sheet, thereby varying the extent of 20 overlap of the members.

2. Sheet decurling apparatus as set forth in claim 1 in which the actuating mechanism comprises a reciprocating frame operatively connected to a movable decurling member and in which 25 the adjusting device varies the position of the frame at one limit of its reciprocating movement.

3. Sheet decurling apparatus as set forth in claim 1 in which the actuating mechanism includes a rocking frame supporting a movable decurling member and a reciprocating actuating element having a radially adjustable engagement 30 with the frame.

4. Sheet decurling apparatus comprising registering decurling members on opposite sides of the 35 plane of a traveling sheet, actuating mechanism for shifting a member into decurling position adjacent to and overlapping the other member including a reciprocating frame carrying the shifted member and a support for the frame, and an 40 adjusting device arranged to shift the position of the frame on the support in a direction transverse to the plane of the sheet, thereby varying the extent of such overlap.

5. Sheet decurling apparatus comprising a stationary decurling member located at one side of the plane of a traveling sheet, a registering movable decurling member at the other side of said plane, actuating mechanism for shifting the movable member into decurling position adjacent to 50 and overlapping the stationary member, and a device for adjusting the spacing of said members in decurling position in the direction of sheet travel.

6. Sheet decurling apparatus comprising registering decurling members on opposite sides of the plane of a traveling sheet, and actuating mechanism for moving a first decurling member from a position below said plane into decurling position adjacent to and overlapping the other member, including a reciprocating frame above 55 said plane and supports connecting the moving member with the frame and extending across the plane of the traveling sheet at either side of the sheet path.

7. Sheet decurling apparatus comprising a stationary decurling member located at one side of the plane of a traveling sheet, a registering movable decurling member at the other side of said plane, actuating mechanism for shifting the movable member into decurling position adjacent to 70 and overlapping the stationary member, and a device for adjusting the spacing of said members in decurling position in the direction of sheet travel, including a support for the movable mem-

ber and an adjustable guideway construction engaging the support.

8. Sheet decurling apparatus comprising a stationary decurling member located at one side of the plane of a traveling sheet, a registering movable decurling member at the other side of said plane, actuating mechanism for shifting the movable member into decurling position adjacent to and overlapping the stationary member, and a device for adjusting the spacing of said members in decurling position in the direction of sheet travel, including a pivoted guideway for the movable decurling member adjustable about its pivot to shift the path of said movable member.

9. Sheet decurling apparatus comprising a stationary decurling member located at one side of the plane of traveling sheet, a registering movable decurling member at the other side of said plane, actuating mechanism for shifting the movable member into decurling position adjacent to and overlapping the stationary member, and a device for adjusting the spacing of said members in decurling position in the direction of sheet travel, including a guideway structure adjustable in the direction of sheet travel, the movable decurling member having end portions slidably engaging the guideway structure.

LYNN O. HAYES.

CERTIFICATE OF CORRECTION.

Patent No. 2,339,071.

January 11, 1944.

LYNN O. HAYES.

It is hereby certified that error appears in the printed specification of the above numbered patent requiring correction as follows: Page 3, second column, line 44, beginning with "5. Sheet decurling" strike out all to and including the word and period "travel." in line 53, comprising claim 5, and for the claims now numbered "6", "7", "8", and "9" read --5--, --6--, --7--, and --8--; page 1, in the heading to the specification, line 7, for "9 Claims" read --8 Claims--; and that the said Letters Patent should be read with this correction therein that the same may conform to the record of the case in the Patent Office.

Signed and sealed this 14th day of March, A. D. 1944.

Leslie Frazer
